UNITED STATES PATENT OFFICE.

MELVILLE E. PETERS, OF DENVER, COLORADO.

BOX AND LABEL FEEDING MACHINE.

1,200,757.

Specification of Letters Patent. Patented Oct. 10, 1916.

Application filed April 30, 1914. Serial No. 835,487.

To all whom it may concern:

Be it known that I, MELVILLE E. PETERS, a citizen of the United States of America, residing in the city and county of Denver 5 and State of Colorado, have invented a new and useful Box and Label Feeding Machine, of which the following is a specification.

My invention relates, generally speaking, to a box and label feeding machine, and the 10 object of my invention is to provide a machine that will pneumatically feed cardboard box-shaped blanks from a hopper device in which they are stacked, to pneumatically operating card bending devices in 15 which they are bent up into loose end boxes, and that within the same time the machine is feeding and bending these box-shaped paste-board blanks into boxes; it also feeds 20 gummed finishing paper box covering blanks from a registering table onto the platen of any suitable box covering machine that is at present in use in the paper box making trade, and instantly afterward receives and feeds the now formed loose end boxes from 25 the bending devices to and on top of the finishing blanks as they are fed onto the platen of the box covering machine and directly under the vertically reciprocating plunger of the box covering machine. My box forming and box and label feeding machine is 30 also arranged to operate the box covering machine to which it feeds its loose end boxes and gummed, finishing and covering labels. I attain this object by the mechanism illustrated in the accompanying drawings, in 35 which:

Figure 1, is a side elevation of the improved box and label feeding machine, a portion 40 of the adjustable label holding table also being shown. Fig. 2, is a front elevation of the upper or inclined portion of the machine, the box card plunger being omitted. Fig. 3, is a plan view of the lower frame of the machine, showing the pump 45 cylinders, the operating cams and the levers connected therewith. Fig. 4, is a plan view of the upper portion of the machine, a part of the feed table being omitted. Fig. 5, is a rear view of the lower portion of the frame, 50 showing the pump cylinders, the operating cams, and the levers connected therewith. Fig. 6, is a plan view of the forward portion 55 of the lower member of the frame, showing the box carrying frame and the slidable carriage to which the same is pivotally secured. Fig. 7, is a side elevation of the left hand upper side frame. Fig. 8, is a vertical, transverse, sectional view through the feed table on the line 8—8 of Fig. 9. Fig. 9, is a side view of the forward part of the 60 feed table. Fig. 10, is a side elevation of one of the feed table side guides. Fig. 11, is an end view of the same. Fig. 12, is a side view of the mechanism shown in Fig. 6. Fig. 13, is a vertical, longitudinal section through 65 the card carrying frame, the same being detached from the carriage. Fig. 14, is a front view of the carriage upon which the card carrying frame is mounted. Fig. 15, is a plan view of one of the box receiving and 70 supporting clips. Fig. 16, is a plan view of the forward end of one of the feed table side guides, showing one of the card retaining clips in the act of holding back the body of cards, thus permitting the front card to 75 be withdrawn by the suction feed box. Fig. 17, is a perspective view of one of the card retaining clips shown in Fig. 16. Fig. 18, is a side view partly in section, of the suction 80 box for removing the cards from the feed table. Fig. 19, is a side view of the bracket which supports the suction box for carrying the labels from the table to the box making machine. Fig. 20, is a front view of the bracket shown in Fig. 19. Fig. 21, is a 85 perspective view of a bushing which is supported in a bracket which supports the forward end of the reciprocating bar, which carries the label suction box bracket. Fig. 22, is a perspective view of a beveled gear, 90 having a bushing form of hub through which the forward end of the bar which carries the label suction box bracket passes, and by which the said bar is given a partial rotation by mechanism connected with said beveled gear. Fig. 23, is a rear view of a portion 95 of the stop device upon which the cards drop after they have been removed from the feed table. Fig. 24, is a perspective view of one of the side bend bars, the same being 100 broken away for clearer illustration. Fig. 25, is a perspective view of one of the end bend bars. Fig. 26, is a horizontal sectional view, full size, of one of the end bend bars. Fig. 27, is a perspective view of one of the 105 sockets in which the end bend bars are secured. Fig. 28, is a plan view of one of the slidable brackets in which the sockets for the end bend bars are mounted. Fig. 29, is a side view of Fig. 28. Fig. 30, is a sectional 110 view through a portion of the left hand upper frame, showing the beveled gear

which operates the beveled gear through which the label carrying bar passes. Fig. 31, is a sectional view illustrating the rear end of the label carrying bar, and a portion of the link on the rear end thereof which connects with the operating lever for said bar. Figs. 32 and 33 illustrate the manner in which the end bend rolls operate to bend the ends of a box card or blank around the ends of a plunger. Fig. 34, is a side view illustrating a portion of the piston rod of one of the pumps, the rock arm to which the rear end of said rod is connected, and the cam fork by which said rock arm is operated. Fig. 35, is an end view of one of the cam brackets which effect the tilting of the box carrying frame from a substantially vertical to a horizontal position, and vice versa. Fig. 36, is a side view of the bracket shown in Fig. 35. Fig. 37, is a plan view of one of the brackets for supporting one of the side bend rolls, and the adjustable block to which the same is bolted. Fig. 38, is a plan view of the cross bar which supports the brackets in which the end bend rolls and their sockets are mounted. Fig. 39, is a transverse, sectional view of the same. Fig. 40, is a perspective view illustrating a label and an incomplete loose end box resting thereon. And Fig. 41, is a plan view of one of the cards or blanks from which the boxes are formed, the dotted lines indicating the score lines upon which the sides and ends are bent. Similar letters of reference refer to similar parts throughout the several views.

Referring to the drawings, the frame of my machine comprises a base plate 1, and side frames 2 and 2^A, which are secured to the base plate and project vertically up from it at a sufficient distance apart to receive and support between and on them the various mechanisms that comprise the several features of it. These side frames 2 and 2^A are braced by a cross shaft 3, which extends between and through them adjacent to their upper edges. The top edges of these side standards are inclined downward from their rear ends 2^B for a portion of their lengths, from the end of which they curve upwardly in a short curve 2^C, and then extend horizontally forward for a short distance, and this end 2^D is the front end of the machine. Upon the side frames 2 and 2^A, I place another frame, which I term the upper or card bending frame, which consists of two sides 4 and 4^A, and these sides fit the inclined and curved portion of the top edges of the side frames 2 and 2^A, and are secured thereto. Above this upper or card bending mechanism, there is a card supporting hopper and feeding mechanism, which is supported by two brackets 5 and 5^A, which bolt to a cross tie frame 5^B that extends across and between the side plates 4 and 4^A, and is bolted to them. These

frames and brackets also support the pneumatically operating mechanism that feeds the blank cards, the loose end boxes from their feeding and bending mechanism, and the finishing covering blanks from a registering table 6, together onto the platen 7 of a box covering machine. These several step movements of my machine are performed in successive cycle movements, and they deliver a gummed box covering blank 8 and a loose end paste board box blank 8^A to the platen of a box covering machine, directly below and in alignment with its vertically reciprocating plunger 7^A, at each complete cycle movement of the machine. These several cycle movements will be fully described hereinafter.

The base plate 1 is a substantial cast iron plate, and is provided with a pair of lugs 9 and 9^A, that project from its left hand side. The lug 9^A supports a double bearing, which consists of a pair of boxes 10 and 10^A, that are spaced a short distance apart but are placed in alignment with each other, and another pair of boxes 10^B and 10^C also 90 in alignment but spaced apart and arranged to one side of the boxes 10 and 10^A. The boxes 10 and 10^A support rotatably a shaft 11, which is the power driven and the driving shaft of all of the mechanism of my box and label feeding machine. A belt receiving friction clutch pulley 12, and a reciprocal movement friction clutch 13, is operatively mounted on the shaft 11 intermediate of its ends. This friction clutch is 100 moved to grip or release the clutch pulley through the medium of a spanner crescent 13^A, that partially surrounds a neck portion 13^B, that is formed in the hub of the friction clutch. This crescent is mounted 105 on and secured to a shaft 11^A, that is supported in the bearings 10^B and 10^C. This shaft 11^A is slidably mounted in the bearings 10^B and 10^C, and it is adapted to be connected to a handle, which I do not illustrate, as it is a commonly used element, which may be positioned at the most convenient point to this machine and to the box covering machine that is to be connected to this machine, and is to be driven from this 115 box and label feeding machine. A collar 13^C is secured to the shaft near the box 10, and an expansive spring 13^D is placed between it and the hub of the friction clutch, and acts to normally hold the clutch in engagement with the clutch pulley.

A worm pinion 14 is mounted on and secured to the shaft 11 between the boxes 10 and 10^A, and meshes with a worm gear 14^A, that is mounted and secured on the end of a 125 shaft 15, which I will term the cam shaft, which extends across the base from one side frame 2 to the other side frame 2^A, and is journaled in bearings 15^A that are secured to lugs 15^B, formed on the lower edge of an 130

open space made in and through the side frames 2 and 2^A.

The outer end 11^B of the shaft 11 is squared to receive a crank wrench, by which it may be turned by hand when desired. The inner end of the shaft 11 is provided with a bevel gear 16, which meshes with and drives a bevel gear 17, that is secured on a shaft 18 that is journaled at right angles to the shaft 11, in a bearing 19, that is secured to and projects from the lug 9 of the base plate 1, and its inner end extends to and is journaled in the side frame 2. This shaft 18 extends outwardly beyond its bearing 19, and a sprocket gear 19^A is mounted on and secured to its outer end, the function of which is to enable this card feeding and bending machine to be connected to and to drive a box covering machine through the medium of this sprocket wheel and a suitable roller or other type of sprocket chain, which I do not illustrate but which is adapted to be connected to a similar sprocket wheel on a box covering machine.

The driving shaft 11 drives the cam shaft 15, which supports and rotates a number of cam disks, which are provided with cam grooves that extend into their opposite sides, and these cam grooves are engaged by rollers 30 that are mounted on arms that connect with the different operating features of the machine through suitable connections and operate them in their successive order of time and action.

The first act of the machine during one of its complete cycle movements is to feed a paste board box shaped blank from its blank holding hopper to the bending device, and I will first describe this blank holding hopper and the feeding mechanism by which these blanks are fed one at a time from the hopper to the bending device. The paste board box shaped blank hopper I will hereinafter term the card hopper 20, inasmuch as each one of these paste board blanks is in the form of a flat card of paste board having its corners cut out to leave its sides and ends free to be bent and folded up to form of it a square box, and all of the cards are of the form shown in Fig. 41. This card hopper 20 is a square trough shaped hopper, and it consists of a cast iron flat bottom table portion 21, which is supported on a pair of side frames 5 and 5^A, that bolt to the cross tie 5^B, which is bolted to the side frames 4 and 4^A of the card bending mechanism, and is provided with side boards 22 which are preferably made of wood. This cast iron table portion is provided with a central groove 22^A, along the opposite sides of which I secure steel strips 24, by screws 23, which project up into them from the table. These steel strips support loosely in oppositely arranged apertures that are formed through their sides, the trunnion ends of a row of

rollers 26. Over these rollers an endless belt 27 is mounted, and the cards are placed in the hopper between its side boards on this belt, by an attendant, and they rest on the belt, by an attendant, and they rest on the belt. The hopper is positioned in a downward inclined position toward its discharge end, and it is filled with cards placed close together, and their weight on the belt and rollers causes them to feed continuously in a bunch toward the outlet end of the hopper. This endless belt 27 passes over the upper end of the table and down through a slot 27^A formed through the table at the forward end of the rollers, and it is supported on the under side of the table 21 at its opposite ends by rollers 29 and 30. The roller 29 is mounted in brackets 31, which are secured to the under side of the table. The roller 30 is placed at the end of a belt tightening or take-up lever 32, the outer end of which is forked and hooks over the trunnion ends of the belt roller 30, so as to be easily detachable therefrom. The opposite end of this belt tightener lever 32 is pivotally mounted in the end of a bracket 33, that is secured to the under side of the table. The forked outer end of the lever 32 swings pivotally on its pivotal pin in the bracket 33, and a screw 32^A is threaded to the lever 32, and is screwed against the under side of the table 21, whereby the belt is given the necessary tension to cause it to move satisfactorily under the weight of the cards.

The side boards 22 are secured to the ends of vertical flanges 34, that are formed on a pair of side guides 35. These side guides 35 are right angular shaped castings, the lower part 35^A of which is a square shaped base block portion that is slidably mounted in guideways 36, formed in extensions which project outwardly from opposite sides of the feed table. This base block is provided with stepped portions 37, that form slideways and which fit slidably in the guideways 36 formed in the feed table. These guideways 36 are provided with removable side strips 36^A, that are secured to the guideways by screws 38. These base blocks are mounted on a feed screw 39, having a right hand threaded portion near one end, and a left hand threaded portion near its opposite end. The threaded portions of this feed screw are rotatably supported in suitably threaded nuts 40, that are secured to the under side of the base block by the cap screws 41. The opposite ends of this feed screw 39 project through openings 39^A made in the frames 4 and 4^A, to receive them, and their ends are rotatably mounted in bearing blocks 42 that are secured to the outside surfaces of the frames 4 and 4^A. One of the terminal ends of this feed screw projects beyond one of its bearings, and is arranged to receive a wrench, by which it may be turned to move the side guides toward or away from the center of

the feed table, as this right and left hand threaded feed screw allows the side guides to be moved simultaneously and in unison toward the center of the table to fit smaller sized cards, from the position they are shown in, in which position they receive between them the largest cards the machine can feed and bend into loose end boxes. The forward edge of this table is provided 5 at its central portion with a forwardly projecting lug portion 43, that forms a resting place for the centers of large cards which have a tendency to bend outwardly at the discharge end of the feed table. The forward ends of the vertical flanges 34 of the side guides 35, are provided at their upper and lower edges with projecting lugs 44 and a spindle 45 that is rotatably mounted in the center of the lugs of each of the flanges of 10 each side guide. A collar 46 is secured to the upper ends of these spindles, and rests on the upper lug, and the lower end of each spindle projects beyond the lower lug and a bevel gear 47 is secured to it. These bevel 15 gears mesh with similar sized bevel gears 48, that are slidably mounted on a square shaft 49, the ends of which are reduced to round shouldered ends, that are journaled in bearings 50 formed in the upper side 20 frames 4 and 4^A to receive them, and partially rotate therein. The bevel gears 48 are secured in adjusted positions on the square shaft when the side guides are moved toward the center of the feed table to fit 25 different sized cards, by a pair of crescent ended plates 51, which are secured to the lower lugs 44 of the vertical flanges of the side guides. The crescent shaped end of each plate is arranged to project into a neck 30 portion 53, which is formed in a hub portion formed on each of these gears. Consequently as the guide plates are moved toward or away from the center of the feed table by their feed screw 39, the gears 48 35 are moved along the square shaft and are always held in mesh with the gears 47 by the crescent plates. On each of the spindles 45 of the flanges of the side guides, I mount and secure, preferably by set screws 40 54, a plurality of clips 55, which I term card engaging clips. I preferably illustrate four of these card engaging clips on each spindle. These card engaging clips project through openings 56 formed in the flanges 55 to receive them, to swing inwardly beyond the inner surface of the flanges, and they are arranged and adapted to stand with their outer ends pointing forwardly toward the discharge end of the feed table and normally even with the inside surface of the 60 flanges, and behind a retaining strip 55^A, which is secured to the end of each of the side flanges. These clips are moved by the gears 47 and 48 by means which will be 65 presently described, against the opposite

sides of the stack of cards, they being arranged to engage the card next to the end card and move the whole stack of cards slightly backward in the hopper, and thus take the weight of the whole stack of cards 70 off of the end card, and this end card is removed from the stack of cards and from the hopper by a pneumatically operating air suction impulse action and co-operating mechanism, which I will presently describe. 75 The gear 47 is caused to turn through a partial rotary movement by the gear 48, through the medium of a lever 57, that is secured to and projects from one end of the shaft 49, to the outer end of which one end 80 of a yoke end 58 is pivotally secured. This yoke end is adjustably secured to one end of a rod 59, that extends to near the cam shaft 15, and is adjustably secured to a yoke end 60 that is pivotally connected to one end of 85 a rock arm 61, which is pivotally secured intermediate of its ends to the side frame 2, and its opposite free end is provided with a laterally projecting roller 62 that projects into a cam groove that is formed in the inner 90 side of the cam disk 64, which is secured on the cam shaft 15. This cam groove is arranged to move the rock arm and rod and bevel gears to cause the clips 55, to swing from their normally forwardly projecting 95 position along the sides of the flanges of the side guide in which they are out of engagement with the cards, inwardly from the opposite sides of the hopper and against the cards and backwardly against the cards 100 enough to move the entire stack of cards except the end card backwardly in the hopper, and they move easily backward up the slight incline of the hopper on the endless belt, which in turn moves on the rollers. 105

The air impulse device and mechanism that grips the end card and conveys it to the card bender, is constructed and operates as follows: The air impulse device comprises an air suction nozzle 65, which preferably consists of a rectangular shaped bar of metal, which is provided with an interior air chamber or aperture 66, and the edge of this nozzle that faces the cards is provided with a vertical row of air intake or air suction apertures 67, which extend into its air chamber 66. This row of air inlet and outlet apertures faces the discharging end of the hopper, and the nozzle is made long enough to engage the full 115 width of the largest cards the machine is capable of using. I preferably form the air chamber in the nozzle by drilling a hole lengthwise of the nozzle to close to its lower end, and in order that some of the upper 120 card actuating air holes may be closed up at the top of the nozzle, which is necessary when cards of different smaller sizes than the largest the machine will receive are used, as the machine will take cards varying 125 13

in size from $20\frac{1}{2}$ by $13\frac{1}{2}$ inches square down to cards $1\frac{1}{4}$ by $3\frac{1}{4}$ inches square. I extend into the top end of the aperture a pin 68, which is fitted therein to fill the aperture snugly but to be moved slidably down into it past one, two or more air holes, as desired, and close them, and in order to hold and set the pin at any adjusted point in the length of the nozzle, I place a set screw 69, through its side against the pin. The nozzle is provided with an air inlet aperture 70, to which a nipple 71 is threaded, and suitable pipe fittings are connected to the nipple and extend to and are connected to an air pump cylinder 72, which is mounted on the base plate of the frame. This air pump cylinder is provided with a suitably packed piston head 73, and with an operatively connected connecting rod 74, the outer end of which is pivotally connected to one end of a rock arm 75, the opposite end of which is pivotally mounted on a shaft 75^A, the opposite ends of which are secured in the side frames 2 and 2^A.

One end of a forked lever 76 is pivotally secured to the rock arm 75, intermediate of its ends, and its forked end straddles the cam shaft 15. This forked lever 76 is provided with a lateral projecting roller 78, that extends into a cam groove 79 formed in one side of a cam disk 80, which is mounted on and secured to the cam shaft 15. This cam groove 79 imparts a reciprocal stroke movement to the forked lever 76, which rocks or oscillates the rock arm 75, causing it to impart a reciprocal stroke to the piston head 73 in the air cylinder 72, through the medium of the connecting rods 74, and the alternate outward strokes of the piston cause alternate air suction movement and force in the nozzle through the piping connecting the air pump with the nozzle and the air holes that are open to the atmosphere in the face of the nozzle, which when the nozzle is close to the end card of the discharge end of the hopper, draws it to it by air suction and grips and holds it and instantly afterward the nozzle is moved back from the discharge end of the hopper and conveys the end card to the card stripping device, which releases it from the suction grip of the nozzle, and they drop onto stop strips 81 in a position to be acted instantly on by a reciprocating plunger 82, which moves it into the first set of bending cams, as will be fully explained hereinafter.

In order that the air impulse nozzle may grip and move and deposit each card and return for another card, it must have a reciprocal movement between the discharge end of the hopper and the bending device, and this reciprocal movement is accomplished by the following instrumentalities: The air impulse nozzle is rigidly secured to one end of a reciprocating bar 83, that is slidably mounted in a slot that is formed in a lug 84, that forms a guideway for it, and that is formed in a cross tie, 85, of the machine; the opposite end of this lever is pivotally secured to one end of a link 86, the opposite end of which is secured to one end of a rock arm 87, which is secured on a shaft 88, by a set screw 89, that extends across and is secured in the ends of a pair of upwardly and outwardly projecting brackets 90, that are secured to the top side edges of the hopper frames 4 and 4^A by cap screws 91. The opposite ends of the cross tie 85 are secured to these brackets. This cross tie 85 is provided with a lateral projection 92, that extends from it toward the discharge end of the hopper, that terminates in a forked end portion. The outer end of the forked portion is provided with upwardly projecting lugs 93, against which flat straight strips 94 are secured. These strips I term the card strippers, as they strip each card from the suction grip of the air suction nozzles on the rearward card carrying stroke of the nozzle, as the sides of each card strike against this stripper and stop it, while the nozzle passes by the forked ends of the projecting lugs, and these strippers on the backward stroke a short distance, and the strippers release each card from the nozzle at a point that allows it to drop from them onto the stop strips 81, below them. One end of the shaft 88 carries a lever 88^A, the free end of which is pivotally connected to a yoke end 94^B, which is adjustably secured to one end of a rod 95, the opposite end of which is adjustably secured to a yoke end 96, that is pivotally connected to one end of a lever 97. The opposite end of this lever 97 is keyed to a stud pin 98, which is pivotally mounted in and extends through an aperture formed through the adjacent side plate. This pivotal stud pin extends from the outside of the side plate through and beyond it far enough to receive one end of a lever 99, which is mounted on and keyed to it, and the opposite end of this lever 99 extends to the outer side of a cam disk 101, and is provided at its end with a laterally projecting roller 102, which projects into a cam groove 103 formed therein. This cam groove 103 and the coöperating lever members and connections, with the nozzle, are so relatively arranged that a reciprocal stroke movement is imparted to the nozzle that operatively moves the cards from the discharge end of the hopper to the strippers, and far enough beyond them to allow each card to drop down past the nozzle before it makes its return stroke. Below the strippers, curved chute plates 104 are secured to brackets 105, which are secured to a cross tie 106, that is extended between the sides 4 and 4^A. These curved chute plates act to guide each card

to fall directly onto the stop strips 81, in case its lower edge should move toward the table away from the stripper. The instant a card strikes the stop strips 81, it is engaged by a plunger plate 82, that is secured to the end of a reciprocating bar 108, and is moved against vertical bending rolls 109 and 109^A, that are arranged to bend the end flaps of the cards, as will be presently explained. This reciprocating bar is slidably mounted in a lug 110, that depends from the center of the cross tie 106, and also in a slide-way 112, that is formed in the center of the cross tie frame 5^B, that is secured to the frame 4 and 4^A of the machine, and its reciprocal movement is imparted to it by lever and link connections that extend from it to and are connected to a cam groove in a cam disk on the cam shaft 15, which will be fully described hereinafter.

The stop strips 81 consist of a pair of flat thin strips of metal that are secured at one end to a pair of right angular shaped brackets 113; the opposite portions of which are provided with recessed ends 114, which fit slidably and adjustably over a horizontal bar 115, which is adjustably supported upon a vertical post 116 by a bolt and a butterfly thumb screw, as shown. This vertical post 116 is secured to a head rail 117, by cap screws 118. The horizontal bar 115 is provided with slots 119, and the brackets are adjustably secured to this bar by butterfly thumb nut screws 120, which extend through the slots and are arranged to clamp the brackets to the horizontal bar in adjusted position, toward or away from the vertical post, which is positioned in the center of the bending rolls to permit these stops to receive the smallest, as well as the largest size cards as they drop from the strippers. This vertical post 116 is provided with a slot 121, and the horizontal bar 115, is secured to it by a bolt 122, which extends through the bar and slot and threads into a thumb nut 122^A, on the opposite side of the post, and the horizontal bar, together with its brackets and the stop strips, can be raised and secured to the stop post in adjusted positions. The horizontal bar and the vertical post prevent the cards from falling out under the plunger and back of the side bending rolls.

The plunger plate 82 is reciprocated to move the cards against the side bending rolls by the following mechanism: To the under side of the bar 108, a clip 123 is secured, to which one end of a link 124 is pivotally connected, the opposite end of which is pivotally connected to one end of a lever 125 that is pivotally mounted on the shaft 3. A lever 126 extends from the hub of the lever 125 and substantially at right angles thereto, the free end of which is pivotally connected to one end of a forked

lever 127, the forked end of which straddles the cam shaft 15. This forked lever is provided with a laterally projecting roller 128, which projects into a cam groove formed in the inner side of a cam disk 129, which is arranged to impart an intermittent step and oscillating movement to the forked lever and the link and lever connections between it and the box, to reciprocate the card plunger plate to operatively move each card against the end and side bending rollers and into the box corner, as will be fully described hereinafter. The bending rolls 109 and 109^A consist of two vertically disposed rolls that are of triangular shape in cross section throughout their length, except at their lower ends, where they are provided with an off-set portion 130. This off-set portion is provided with a depending hub portion 131, which fits into and is pinned or otherwise secured to a socket shaft 132. This socket shaft extends rotatably through a bearing block 133, which is secured to the top of the head rail frame 117 and down into a slot 134, that extends longitudinally throughout the length of the head rail frame. The lower end of this socket shaft projects below the bearing block 133, and on it a bevel gear 135 is mounted, which meshes with a bevel gear 136, that is provided with a square axial aperture and is loosely and slidably mounted on a square shaft 137, the opposite terminal ends of which are turned round and are rotatably mounted in bushed bearings formed through the side frames 4 and 4^A. One end of this square shaft projects beyond the frame 4^A, and a lever 138 is secured thereon, which is connected by an arm 38^A with one member 38^B of a rocking lever, the other member 38^C of which is operated by a driving cam that is mounted on the cam shaft, which connection will be fully described hereinafter. There are two of these vertical end flap bending rolls, and the other one, 109^A, is positioned at the opposite end portion of the head rail frame. This side bending roll 109^A, is in all respects like the other side bending roll 109 and is provided with a similar socket shaft connection 132 and with a similar bearing block 133, and the lower end of the socket shaft is provided with a similar bevel gear 135, which meshes with a similar bevel gear 136, that is also slidably mounted on the square shaft 137, the same as the other gear 136. The object of slidably mounting the side bending rolls and their supporting socket shafts and driving gears, is to enable the bending rolls to be moved together in unison and toward and away from the center of the machine, which is defined by the vertical post 116 to receive and bend the end flaps of cards from the smallest to the largest sizes the machine is made for.

This adjustable feed movement 130

of the side bending rolls is accomplished by a shaft 139, that is provided with a right and left hand threaded portion respectively, on opposite sides of its central portion.

5 This threaded shaft 139 is threadedly mounted in suitably threaded bushings 140, that are screwed into one end of each bearing block 133, and at one side of the bearings of the socket shafts. The opposite ends 10 of this threaded shaft extend, rotatably through bearings in the frames 4 and 4^A, in which they are secured against lateral movement so that rotative movement of the shaft causes its threaded portions to move 15 the bearing blocks and the end bending rolls slidably along the slot of the head rail frame. One end of this threaded shaft extends beyond the frame 4 and is arranged to receive a crank wrench, by which it may be 20 manually turned.

The bevel gears 136 are moved along the square shaft 137 by means of crescent levers 141 which are secured to the bearing blocks 133 at one end and extend into neck portions 142 formed in the hubs of these gears. The square shaft 137 is preferably provided with bushed bearings in the frames 4 and 4^A in order that it can be readily withdrawn. This shaft and its gears and the end bending rolls 25 are given an oscillating movement through the medium of the lever 138, which is pivotally secured to one end of the arm 38^A, the opposite end of which is pivotally secured to one end of an arm 38^B, the opposite end of 30 which terminates in a hub 38^D, which is pivotally mounted on a pin that is secured to the left hand frame 4^A. From the opposite side of this hub, an arm 38^C projects, that is provided at its end with a cam roll 38^E, which 35 engages a cam groove formed in the outside face of a cam disk 38^F, which is mounted on the cam shaft 15, outside of the left hand frame 4^A. The cam groove of this cam disk 38^F is arranged to give an eccentric throw movement to the double armed hubbed levers 38^B and 38^C, and to the arm 38^A and the lever 138, that will impart an oscillating stroke to the 40 gears and end bending rolls of sufficient movement to bend the end flaps of the cards, as shown in Figs. 32 and 33. These bending rolls are hollow, being each provided with an air chamber 143 that extends lengthwise of each of them through their card end bending portions, and from these chambers a 45 vertical row of air suction inlet apertures 144 extend through the shell of that side of each bending roll that faces the plunger plate 82. The air chambers in these end bending rolls are preferably round holes that 50 are drilled down into them. Each bending roll is provided with an inlet nipple, to which one end of a flexible tube 145 is connected, the opposite ends of which tubes extend to 55 and are connected to an air pump cylinder 146, both pipes being connected into one

fitting at the cylinder. A suitable piston is reciprocally mounted in the cylinder, which is connected by a connecting rod 147 to one end of a rock arm 148, which is pivotally mounted at its opposite end on the shaft 75^A 70 that extends across between the side frames 4 and 4^A. The rock arm 148 is pivotally connected intermediate of its ends, to one end of a forked lever 149, the forked end of which straddles the cam shaft 15. This forked lever is provided with a laterally projecting roller 150, intermediate of its ends, which projects onto a cam groove formed in the outside face of a cam disk 151. This cam groove is arranged and adapted to impart, 75 through the medium of the forked lever, the rock arm and the connecting rod and piston, a suction air force in the pump cylinder 146, which draws the end flaps of the cards tightly 80 to the bending rolls and holds them there while the flat sides of these bending rolls make their oscillating movement and bend and break them along their scored lines, as 85 shown in Figs. 32 and 33.

The plunger, which is of the width of the body of the size of cards being run through the machine, and which requires changing to fit each size cards when the size of cards is changed, moves on its card feeding stroke with an intermittent step by step movement, 90 which is as follows: When a card drops from the strippers onto the stop strips this plunger moves against its central body portion inside of its side and end flap portions and moves it up against the sides of the bending rolls and 95 stops there, while the air suction grips its end flaps and draws them against the flat side of these rolls and they move around the ends of the plunger and carry the end flaps with them, thus breaking the cards 100 along their scored lines, as above mentioned. The rolls then turn back and then the plunger starts and moves the card with its 105 bent ends through and past the rolls and against the horizontally positioned side 110 flaps' bending rolls, and then the plunger stops again, which I will now describe, but will state here that after the side flaps are bent over, this plunger again proceeds forward and pushes the now completely formed 115 loose end box into the swinging box feeding frame, which will be presently described, after which the plunger returns to the starting point of its reciprocal stroke.

Each of the side bending rolls 152 and 153 120 consists of end portions in alignment with each other, having a narrow collar portion at one end and a long roller portion adjacent to its opposite end portion, and with a long 125 triangular arranged flap bending portion that is arranged eccentric to the axis of the round end portion, between the two collar portions, the center or thinnest edge of which is along the axial center of the collars and opposite end portions of the rolls. 130

The triangular side flap bending portion of the rolls is provided with an air chamber 154, which is preferably made by drilling a hole down into it from preferably its narrowest collar end. The face of the triangular flap bending portion of the roll is provided with a row of air suction apertures 155, that extend through it into its air chamber, all of said apertures, as well as all of the 10 apertures in the end bend rolls, being employed in forming boxes of the greatest dimensions of which the machine is capable, but when blanks for boxes of smaller sizes are used, the apertures both in the end and 15 side bend rolls, outside the ends and sides of the blanks, are closed by pasting paper over them, or by covering them with a suitable adhesive material. Each of these bending rolls is provided with an air passage nipple, and apertures that enter the air chamber within them, and suitable piping is connected to and extends from each roll and is connected into one pipe which is connected to an air pump cylinder 156, which is provided with a 20 suitable piston and connecting rod 157, which is connected to one end of a rock arm 158, the other end of which is pivotally mounted on the shaft 75^A. This rock arm is connected intermediate of its ends, to one end of a 25 forked lever 159, the forked end of which straddles the cam shaft 15. This forked lever is provided with a laterally projecting roller 160, which projects into a cam groove that is formed in the inside face of the cam 30 disk 80, that is mounted on the cam shaft 15. This air pump during the outward strokes of its piston, creates an air suction force in each of the side bending rolls that draws and 35 grips the cards tightly against their card engaging surface of each roll while the rolls are bending the side flaps of the cards around the side edges of the plunger, which, when this suction action occurs, has moved a card past and from the end bending rolls against 40 these side bending rolls.

The side bending rolls are pivotally mounted at one end in head blocks 161, and at their opposite ends in bearing brackets, which are bolted to bracket arms 162, which 45 are bolted at their opposite ends to the head blocks 161. These head blocks are provided with shouldered slideway portions which fit 50 slidably in a vertically disposed slideway slot 163 that is formed in the frame 4. This 55 frame 4 is extended forward beyond the frame 4^A, far enough to allow this slideway slot to be formed in it, and the bracket arms 162, as well as the side bending rolls, are 60 arranged to be adjustably fed to and from the horizontal center of the card bending devices by a shaft 164, that is provided with right and left hand screw threads, which are 65 threaded in bushings that are inserted in the blocks 161. The upper end of this threaded rod is rotatably mounted in a suitable cap

165, through which it extends, and its terminal end is arranged to receive a suitable wrench by which it may be turned. In order to prevent the accidental turning of this threaded rod under the weight of the bracket 70 arms, I thread a set screw 166 through the cap 165 against it. The side bending rolls 152 and 153 are rotatably mounted to stand facing each other. At the outer free ends of the arms they are rotatably mounted in bearing brackets 167, which are secured to the 75 ends of the bracket arms. The ends of the bending rolls which are journaled in bearing apertures formed in the head blocks, extend beyond the head blocks, and a pinion spur 80 gear 168 is mounted on and secured to each end. These spur gears 168 mesh with spur gears 169, which are mounted on and are secured to the hubs of bevel gears 170, that are rotatably mounted on stud bolts, that are 85 threaded into the head blocks 161. The bevel gears 170 mesh with bevel gears 171 that are 90 slidably mounted on a square shaft 172. The upper end of this square shaft is rotatably journaled in an extension 173 of the cap 165. At the lower end of the square shaft 172, there is a bracket bearing 174, that is secured to the frame 4 of the machine by cap screws. 95

On the lower end of the shaft 172, is a bevel gear 175, the hub of which fits rotatably in the bearing 174 and extends beyond it far enough to have formed in it a neck portion in which a yoke or crescent shaped plate fits loosely, which is secured to the adjacent end of the bearing by screws 176, and is adapted to secure the gear in the bearing. The bevel gears 171 on the square shaft are held in mesh with the bevel gears 170, as the bevel gears and spur gears are moved toward or away from each other, by the turning of the threaded shaft 164 to adjust the side bending rolls to fit the different sized cards used in the card bending and feeding machines, by crescent plates 177, that are secured at one end to the head blocks 161, 100 and are provided with a recessed end that fits loosely over and in a neck portion that is formed in the hubs of the gears 171. The lower gear 175 meshes with a bevel gear 178 that is supported on a stud screw that is secured to the frame 4, and on the hub of this gear 178, one end of a lever 179 is secured, the opposite end of which is pivotally secured to one end of a connecting rod 180, the opposite end of which is pivotally connected to one end of a rock arm 181, at the pivotal center of which a hub is formed, which is secured to the frame 4 by a stud screw, and from this hub an arm 182 extends, the end of which is pivotally secured to one end of a forked lever 183, the forked end of which is arranged to straddle the cam shaft 15. This forked lever is provided intermediate of its end, with a laterally projecting roller 184, which projects into a cam 110 115 120 125 130

groove formed in the inner side of the cam disk 64, which is mounted on the cam shaft 15. This cam groove is provided with an eccentric throw that is sufficient, through 5 the parts connected with it that are connected with the gear 178, to impart an oscillating movement to each group of gears that are connected to each of these side-bending rolls, to impart to these side-rolls an oscillating movement of sufficient stroke to bend 10 the side flaps of the cards as far around as is desired.

The side flaps of the cards having been bent, the card has been completely formed 15 into a loose end box, and instantly after the side rolls have swung back into their normal card receiving position, the plunger plate 82 is again moved forward and carries 20 the now completed loose end box into the box carrier, which, when it has received it, swings down into a slideway and the box carrier feeds it forward and delivers it onto the platen 7 of a box covering machine. This box carrier consists of oppositely ar- 25 ranged side bars 179', which are secured at their lower ends to brackets 180', the opposite ends of which are slidably secured to a cross base plate 181', and which is provided with slots 182', through which bolts 183', 30 which secure the bracket to this base plate, extend.

In slots 184' in the side bars 179', I adjustably secure by butterfly thumb screws 185, a pair of loose box receiving and sup- 35 porting clips 186, one being positioned at each end portion of the slots of the bars, which, as represented, are positioned to receive the largest size of loose end boxes the machine will receive, but which are provided 40 with lug portions 187, that project into the slots and hold the clips slidably in the slots in position to receive the now formed loose end boxes at all times, and that allows the clips to be moved slidably along the slots 45 of the bar, and the bars themselves can be moved along the base plate 181 in its slots 182, so that these clips will receive all four corners of the smallest size loose end boxes made, which is represented by the dotted 50 lines in the center of Fig. 6, which represents a plan view of this box carrier with a loose end box of the largest size, in position to be deposited on the platen 7 of a box covering machine. The clips 186 are of 55 right angular shape and are provided with intersecting beveled surfaces that taper from their thickest rear side and end portion to their front edge box discharging edges, in order that they may offer the least resistance 60 to the discharge of the boxes from them.

The base plate 181 is secured to a square bar 188, which I term the box carrier lifting bar, by screws 189. Upon the opposite terminal ends of this lifting bar, are rigidly 65 secured cam levers 190, the opposite ends of

which are provided with lateral pins 191, which carry rollers 192 that slide reciprocally on runways formed on a pair of oppositely arranged cam brackets 193, which are secured to the insides of the side frames 70 2 and 2^A. The upper edges of these cam brackets are provided with laterally projecting introverted lips 194, the underside of which forms a slideway for the rollers 192, which are secured on the pins 191 of the cam 75 levers 190. Adjacent to the terminal ends of this square shaft 188, bearings are formed that are journaled in boxes 195, formed on the forward corners of the ends of a sliding carriage 196. The ends of this sliding carriage are provided with slideway grooves 197 throughout their entire lengths, which are slidably mounted on track bars 198 that are secured at their opposite ends to brackets 199 and 200, which are secured to the inside 80 of the frames 2 and 2^A. The carriage is thus secured to the base bar and base plate and the box carrying frame by the boxes on its slideway ends, and all these parts are moved reciprocally by levers connecting with a 85 driving cam located on the driving shaft, which will be presently described. The box carrying frame, however, as soon as it receives a loose end box from the bending rolls and the plunger swings from its vertically 90 disposed position in which it receives the box, down into a horizontal position over and ahead of the carriage, and as it reaches the end of the outward stroke of the carriage and its reciprocal movement, it deposits its 100 box on top of a box covering and finishing label 8, the box being removed from the box carrier by the downward reciprocal movement of the box covering machine's plunger 7^A, which moves down centrally into the 105 body portion of the loose end box, and then this box carrier starts back on its return stroke, and as the end of this box carrying frame is open, the box clips at the outer end of the carriers, owing to their being thin, 110 readily move from under the box.

When the box carrier is in its vertically disposed position ready to receive a box from the plunger, the roller ends of the box frame lifting levers 190 engage downwardly curved 115 rear end portions of the cam brackets 193, but as soon as the box carrier receives a box from the plunger, the box carrier swings down into a horizontal position, and is moved forward with the carriage to the end of its 120 and the carriage's forward stroke, during which movement the roller ends of the levers 190 travel upwardly against slideways 194 of the cam brackets. The levers 190 being rigid on the shaft 188, are held in continuous engagement with the slideways 194, by the weight of the box carrying frame, which is in a forwardly inclined position when in its box receiving position. As the carriage moves forward, the engagement of the lever 125 130

rollers 192 with the inclined portions of the slideways 194, causes the carriage to gradually assume a horizontal position; and as the carriage moves rearward, the box carrying frame is raised to its box receiving position, by the engagement of the said rollers 192 with the said inclined portions of the slideways 194. The reciprocal sliding movement of the carriage and base plate and box frame 10 on the tracks 198, is imparted to them by means of the following levers.

The carriage is provided at the center of its rear edge with a pair of ears 201, between which is pivotally secured one end of a link 15 202, which I term a box carrier link, the opposite end of which is pivotally connected to one end of a rock arm lever 203, the opposite end of which is integrally connected to one end of a long hub 204, that is mounted 20 on the shaft 205, that extends between and through the side frames 2 and 2^A. From the opposite end of this hub, but in line with the lever arm 203, projects a lever 206, which is pivotally secured at its free end to the end of 25 a forked lever 207, the forked end of which straddles the cam shaft 15. This forked lever is provided with a laterally projecting roller 208, which extends into a cam groove formed in the inner side of the cam disk 30 101. This cam groove is arranged and adapted through the medium of the forked lever 207 and the rock arms 203 and 206, to impart a reciprocal movement to the box carrier and its supporting carriage, sufficient to 35 deposit it on top of a label on the platen 7 of a box covering machine, which does not form a part of this invention.

My improved loose end box and label feeding machine is also adapted to feed labels 40 from a registering table onto the platen 7 of a box covering machine at the same time or a trifle in advance of the instant the loose end box arrives at the center of the platen 7, in order that the loose end box may be deposited centrally on top of the label, so that 45 the plunger of the box covering machine may carry both the box and its covering label into the box covering machine and cover it in a manner well known in the art of making paper boxes. This label feeding mechanism 50 consists of a bar 209, preferably a square bar, which is supported in bearings 210 and 211 that are attached to the box covering machine in any suitable manner. This bar 209 is a square reciprocating bar and is consequently slidably mounted in the bearings 210 and 211. It is also necessary that it turn or oscillate through a part of a full revolution on its longitudinal axis, and in order that it 55 may accomplish both a longitudinal and a partial rotative or oscillating movement on its axis in its supporting bearings, I arrange these bearings in the following manner: The bearing 210 comprises a bracket that is detachably secured to the frame 2^A, of the box

covering machine. The free end of this bracket is provided with a capped journal box, in which a sleeve 212 is rotatably mounted, and this sleeve is provided with a square axial aperture 213, through which the square box 209 extends slidably, while the bar and sleeve are free to rotate or turn through a part of a full revolution, which I preferably limit to a quarter of a revolution, as will be hereinafter fully described. The bearing 211 75 comprises a capped journal box that projects from a bracket portion that is detachably secured to or forms an integral part of the frame 4^A, and this capped journal box is arranged to receive rotatably the hub portion 80 214 of a bevel gear 215, which extends loosely through and beyond it and is provided with an integral collar 216 at its end by which it is held against endwise movement in its bearing. The bevel gear is provided with a 85 square shaped axial aperture through which the bar extends loosely and slidably, and it is this gear which effects through another gear 217 and other co-operating mechanism, the quarter turning or oscillating movement 90 of the square bar 209. This gear 217 is supported on one end of a spindle 218, which is pivotally mounted in the frame 4^A, and to which it is keyed or otherwise rigidly secured. To the inner end of the spindle 218, 95 is rigidly secured a lever 219, the outer end of which is pivotally secured to one end of a lever 220, which is pivoted at its opposite end to one end of an L-shaped rock arm 221, the opposite end of which is pivotally mounted 100 on one end of a pin 222, extending through the frame 2^A, and upon the other end of which is mounted the hub 38^B of the levers 38^B and 38^C. The heel of this rock arm is provided with a roller 223, which is arranged 105 to project into a cam groove formed in the outer face of the cam 129, which is mounted on a driving shaft 15. The cam imparts sufficient movement to the rock arm 221 and the lever 219, to cause the gear 217 to turn a 110 quarter of a revolution, which rotary movement is imparted to the gear 215, and it is turned a quarter of a revolution and it turns the square bar 209 a quarter of a revolution, and as it does so, it turns an adjustable 115 bracket 224, which is adjustably mounted on the opposite end of the bar 209. This adjustable bracket 224 is secured in adjusted positions by a set screw 225, and it supports at its free end the air impulse device 226, 120 that grips the blanks and conveys them to the platen 7 of the box covering machine, and releases them at a point where the boxes will register on them. This air impulse box will be described hereinafter.

The rear end of the square bar extends a short distance beyond the bevel gear 215, and to its end a block 227 is rotatably secured. This block 227 is rotatably mounted on a reduced round shouldered portion 228 that is 125 130

formed on the terminal end of the square bar 209, and into opposite sides of the block are inserted screws 229, which secure the yoked ends of a link 230, the opposite end of which is also yoke-shaped and is pivotally connected to one end of an L-shaped crank lever 231. This crank lever is pivotally supported at its heel portion upon a pin or bolt 232, which is mounted in the frame 2^A, while its 5 shorter member 233 is pivotally secured to one end of a yoke lever 234, the opposite end of which is provided with a forked end that extends to and straddles the driving shaft 15, which acts as a support for the forked end 10 of this lever, and permits it to slide reciprocally thereon. This forked lever is provided with a roller 235 which is secured to it intermediate of its ends. This roller is arranged to project into a cam groove formed in the 15 inner face of the cam disk 38^E, which is mounted on and is secured to the cam shaft 15, and is arranged to impart a reciprocal throw stroke to this forked lever and to the crank lever 231 connected to it and to the 20 link 230, to impart an intermittent reciprocal stroke movement to the square bar 209, while the block 227 permits the bar to be turned through a quarter of a revolution on the inoperative stroke of its reciprocal movement, 25 as will be fully described hereinafter.

It is essential that the bracket 224 at the forward end of the bar 209, have a quarter turn movement on its backward or inoperative stroke of its reciprocal movement, in 30 order that the air impulse box at its end may pass by the form block 7^A of the box covering machine, because the form block moves immediately down against the platen the instant after a finished blank has been 35 deposited at the box registering point of the platen 7, and this form block is consequently in the path of the return movement of the outer end of the air impulse box. Consequently the square bar 209 is positioned 40 far enough to one side of the form block 7^A to entirely clear it on its reciprocal strokes, but it is necessary that the air impulse device at its free end be arranged so that on its operative blank moving stroke it 45 will move centrally underneath the form block 7^A, in order that it may deposit the finishing blanks centrally underneath it, inasmuch as the loose end box that the finishing blank is to cover, is fed directly 50 on top of the finishing blank instantly after the label is deposited on the platen. Consequently, in order that the air impulse box 55 may avoid contact with the form block 7^A on its back stroke, the air impulse device 60 must be moved to one side of the form block at the time it starts to move on its backward stroke to grip another blank, and this form block clearing movement of the air impulse device is accomplished by causing the 65 bracket to turn from the downward vertical

position it stands in when the air impulse box is in air gripping relation to the blanks, to a horizontal position, which change of position it accomplishes by being moved through a quarter circle turning movement 70 by the bar 209, which quarter turning movement turns the air impulse device also from the horizontal position in which it receives and grips the finishing blank, and moves it over to and deposits it on the platen and 75 continues to the end of its operative stroke, at which point it is swung up and changed from its operative horizontal position into a vertical position before it starts back on its backward stroke, which moves it out of the 80 path of the form block and allows it to pass the form block 7^A on its return backward and inoperative stroke. When, however, it has passed the form block 7^A, and before it reaches the end of its backward stroke, it is 85 again turned down into its horizontal position and completes the remainder of its stroke in that position and moves under at the end of its backward stroke another finishing blank which the air impulse draws 90 down against it with a gripping force that holds it firmly to it, after which it again starts on its operative blank feeding stroke and moves it over onto the platen 7, and thus repeats, the cycle of its reciprocating 95 movement; and these two quarter turning movements of the bar 209, its bracket 224, and the air impulse blank gripping device are accomplished by the gears 215 and 217, and their coöperating levers and the cam 100 38^E, while the rod 209 is being moved on its backward stroke by the cam 38^E, and its connecting levers and the link 230, as will be fully explained hereinafter.

The pneumatic impulse device 226 that 105 grips and moves and releases the blanks in alternate order from their gummed location to a predetermined position on the platen 7, where the boxes to be covered will register on top of them, may be made in a number 110 of ways, but as illustrated, it preferably comprises a member in the form of a channel bar, which is secured in a longitudinal recess in the bottom of the bracket 224. This channel bar is closed by a metal strip 236, 115 which is provided with a row of air inlet and outlet apertures 237, which extend the full length of the strip. This air impulse box is made long enough to grip the largest size blanks that are to be used, and when 120 blanks are used that are of smaller size than the largest size blanks used, the air holes in the strip outside of these smaller or narrower blanks can be closed by pasting pieces of paper over them. The air box is preferably 125 made to feed blanks for boxes of different sizes ranging from about 13 $\frac{1}{2}$ by 20 $\frac{1}{2}$ inches square, down to boxes of about 1 $\frac{1}{4}$ by 3 $\frac{1}{4}$ inches square.

The table 6 upon which the blanks are 130

placed and registered to be gripped by the air impulse box, is adjustably and slidably mounted on a supporting frame 238, by means of a bracket 239, that allows it to be moved and adjustably set by any suitable means toward or away from the platen 7, of the box covering machine, to accommodate it to receive small or large size finishing blanks in a registering position that will permit them to be gripped by the air impulse box, and the bracket 224 may be adjusted to accommodate the air impulse box to small or large finishing blanks.

As illustrated, the top of the frame 238 is provided with a bolt receiving slot 240, in which the bracket 239 of the table 6 is arranged to slide, and bolts 241, having properly shaped heads, fit into the slots and clamp the bracket 239 of the table to the top 20 of the frame in adjusted positions. The air impulse box 226 projects from the horizontal member of the bracket 224, and when in an operative blank moving position stands in a horizontal plane. The horizontal member bracket 224 is provided with an entrance aperture, in which is screwed a nipple 242, to which one end of a piece of hose 243 is secured. This hose extends to and is secured to one end of a pipe 244, the 30 opposite end of which is secured to the air actuating end of an air pump 245, which is preferably mounted on the base plate of the box covering machine in a position to be actuated from the driving shaft 15 of the machine. This air pump comprises a cylinder, provided with a suitably packed piston head, from which a piston rod 246 extends, and at its outer end it is pivotally connected to one end of a rock arm 247, the opposite 40 end of which is pivotally mounted upon the shaft 75^A. This rock arm 247 is also pivotally connected to one end of a forked lever 248, the opposite end of which straddles the driving shaft 15 slidably. This forked lever 45 is provided intermediate of its ends with a laterally projecting roller which projects into a cam slot that is formed in the inner face of the cam disk 151, which is mounted on and is secured to the driving shaft 15. This cam 151, the forked lever 248 and the rock arm 247, act under the rotative action of the driving shaft to reciprocate the piston rod and piston head in the cylinder.

The operation of my box and label feeding machine is as follows: The feed hopper having been provided with a supply of cards which feed continuously by gravitation on the endless belt upon which they rest, to the discharge end of the hopper, where they are held by the corner retaining strips 55^A until they are moved slightly back by the clips, when the suction nozzle 65 grips the end one and removes it from the hopper. Power is then applied to the friction clutch pulley

through a power driven belt. The cam shaft 65 15, and the several cams thereon are rotated. These cams operate the different mechanisms of the machine and the air suction card feeding nozzle and the card pressing relieving clips operating cam and connecting levers and members, and the forward feeding movement of the air suction nozzle up to the cards are the first to act. The clips move into engagement with all of the pack of cards except the end card, and move 75 the whole pack back just enough to take the weight off of the end card, and instantly afterward the air suction nozzle moves against the end card and grips it by air suction force and holds it to the nozzle and 80 conveys it against the strippers which remove it from the nozzle, and drops onto the stop strips in front of the plunger, which moves it against the end flap bending rolls, at which point the plunger stops 85 until the end flaps are bent around the ends of the plunger. These rolls grip it by an air suction force and hold it while the flat sides of the triangular segment of these rolls as it turns, carries the end flaps of the cards 90 around the corners of the plunger, as is shown in Fig. 33. Some card boards require that the flaps of the cards be bent around to about an angle of thirty degrees, while other card boards of stiffer quality or 95 of different thicknesses do not require that the flaps be bent around that far. The air suction holds the end flaps tightly against the flap engaging surface of the triangular shaped flap bending rolls, and they are 100 turned forward to carry the end flaps around the side edges of the plunger and then turn back again into their inoperative flat flap receiving position. The bent end flaps naturally spring backward a little, but 105 remain at about a bent up angle of about eight to twelve degrees from the right angles, with the bottom or body portion of the card. The first step forward movement 110 of the plunger and the end flap bending and returning movements of the end flap bending rolls remain but a few seconds of time. The plunger then moves forward again and pushes the card through between the end bending rolls and against the side bending 115 rolls, where it again stops, and these side bending rolls grip the side flaps by suction and bend them around the side edges of the plunger in the same manner. The box is then formed, and is known as a loose-end 120 box, as while its sides and end flaps are bent up, they are loose and free from each other. The plunger again moves forward and carries the box between and past the side rolls and pushes it into the box carrying frame and between the angular and beveled walls of its clips, and with its bottom or body portion extending a short dis-

tance past or close to the outer ends of the clips, which are beveled to receive the loose end corners of the box with tapering angular surfaces that register near enough to 5 the taper of the corners to hold the box from falling through the clips and box carrier frame.

Having pushed the box into the box carrier, the plunger starts back on the rearward stroke of its reciprocal movement, and the 10 box carrier is swung down and moved forward with its supporting carriage in the slideways of their supporting frames, toward the platen 7 of a box covering machine, 15 and at the same time the box is being carried forward toward the platen 7. The label feeding air impulse nozzle has drawn and gripped a label by air suction force, and is being moved toward the platen 7 by its reciprocal mechanism, and this label feeding mechanism is so relatively arranged to 20 the box feeding movement toward the platen 7, that the box is fed over and deposited on top of the label at the platen, and arrives at 25 the platen at the same time as the label, and at the instant the label and box arrive, the plunger 74 of the box covering machine descends into the box against its bottom or body portion, and carries both the box and 30 its covering label down into the covering machine, which I do not illustrate, as it does not form a part of my invention. This box covering machine is, however, operated by 35 my box and label feeding machine through the medium of the chain that extends from the sprocket wheel 19^A, which is driven from the driving shaft 11 of the machine.

Having described my invention, what I 40 claim as new and desire to secure by Letters Patent, is:

1. A box-forming machine comprising a card hopper, a platen, card-bending rolls, means comprising a pneumatic suction nozzle and a plunger for feeding cards from 45 said hopper to said rolls, and means for carrying the cards from said rolls to said platen.

2. A box-forming and covering machine comprising a card hopper, a label support, a platen, card-bending rolls, means for feeding labels from said support to said platen, 50 means for carrying said cards from said hopper to said rolls, and means for carrying said cards from said rolls to said platen on top of said labels.

3. A box-forming and covering machine comprising a card hopper, a label support, a platen, card-bending rolls, means for feeding labels from said support to said platen, 55 means comprising a pneumatic suction nozzle and a plunger for feeding cards from said hopper to said rolls, and means for carrying the cards from said rolls to said platen on top of said labels.

4. In a box-forming and covering ma-

chine, a platen, a plunger above said platen, 65 a label support, pneumatic means for transferring labels from said support to said platen, and a box carrier comprising a frame and a reciprocating carriage to which said frame is pivoted for feeding boxes from said forming machine to said platen on top of said labels, said plunger arranged to then move said label and box out of the path of the box and label-feeding mechanism.

5. In a box-forming and feeding machine, 75 a frame having a slideway, a platen, bending rolls, a plunger for feeding box-cards to said bending rolls, a box carrier mounted on said slideway for receiving the bent cards from said plunger, and means for causing 80 said carrier to receive and convey the box from said plunger to said platen.

6. In a box-forming machine, a frame having cam grooves therein, a platen, means for bending the cards, means for transferring the cards from said bending device to 85 said platen, said means comprising a sliding carriage mounted on said frame, a card carrier pivoted to said carriage, means for reciprocating said carriage, means for oscillating said card carrier comprising arms attached to and extending rearwardly from 90 said carrier, cam rollers on the ends of said arms adapted to project into said cam grooves, said grooves being so curved as to 95 cause the carrier to oscillate as the carriage is reciprocated.

7. In a box-forming machine, a frame, a platen, means for bending the cards, means for transferring the cards from said bending 100 device to said platen comprising a carriage slidably mounted on said frame, a card carrier pivoted to said carriage, means for reciprocating said carriage, and coöperating means on said frame and said carrier for 105 reciprocating said carrier as said carriage is oscillating.

8. In a card-carrying device for box-forming machines, a frame, a carriage slidably mounted on said frame, journal boxes on 110 said carriage, a card carrier having a squared shaft mounted between and journaled in said boxes, the ends of said shaft extending beyond said journal boxes, a base board attached to said squared shaft and 115 having a pair of longitudinal slots extending inwardly from each end, cross-plates adjustably secured in the slots, a side bar attached to each cross-plate and extending transversely of said base board, each of said 120 side-bars having a longitudinal slot in its outer end, and box-receiving clips adjustably mounted in the slots in said side bars, means for reciprocating said carriage, and means for oscillating said carrier while said carriage is being reciprocated.

9. A card-bending device comprising a card support, a plunger for carrying said

- card, a set of bending rolls in the path of movement of said plunger, card gripping means on said rolls, means for operating said plunger and means for oscillating said rolls.
10. A card-bending device comprising a card support, two sets of rolls for bending the edges of the cards, an intermittently operated plunger for moving the card from said support to one set of said rolls, and then to the other set of rolls, card-gripping means on said rolls, means for operating said plunger, and means for oscillating said rolls.
15. In a box-forming machine, a frame, a card hopper, two sets of bending-rolls, means for feeding cards from said hopper to said bending-rolls, a box carrier, a plunger having a flat portion positioned to engage cards as they are fed from said hopper and to feed them to said rolls, said flat portion being of the size of the cards, a bar secured to said flat portion and slidably supported in said frame, means for reciprocating said plunger to move the cards successively to said sets of bending rolls, and then to move it to said box carrier, and means for interrupting the travel of said plunger during bending of the cards.
20. In a box-forming machine, the combination of a label-supporting table, a card hopper, a platen, rolls for bending the cards into boxes, means for feeding the labels from said table to said platen, and means for transferring the boxes to said platen on top of said labels.
25. In a box-forming machine, the combination of a label-supporting table, a card hopper, a platen, rolls for bending the cards into boxes, means for feeding the labels from said table to said platen, means including a pneumatic nozzle and a plunger for feeding the cards to said rolls, and a carrier, for transferring the boxes from said rolls to said platen.
30. In a box-forming machine, the combination of a card hopper, a platen, label supporting table; rolls for bending the edges of the cards, a pneumatic nozzle for feeding cards from said hopper to said rolls, an intermittently operated plunger, a carrier for transferring the boxes to said platen, said plunger receiving the cards from said nozzle and moving them to said edge-bending rolls, and then past said rolls to said box carrier.
35. A box-forming and label-feeding machine, comprising a card hopper, a platen, a pneumatic nozzle for gripping and feeding cards from said hopper, bending rolls provided with pneumatic card-holding means, a plunger for transferring the cards from said nozzle to said rolls, a box-carrier receiving boxes from said plunger and delivering them to said platen, and a pneumatic label-feeding mechanism for trans-
- ferring the labels from said support to said platen.
40. A card-bending device, comprising bending rolls, a reciprocating plunger having an intermittent movement for feeding cards to and beyond said rolls, each of said rolls having a flat side for receiving the edges of the cards from said plunger, mechanism for operating said rolls to swing them and the edges of the cards around the edges of said plunger a predetermined distance during the period of time in its stroke when said plunger is at rest.
45. A box-forming machine, comprising a plunger, a box-carrier, bending rolls, a plunger for feeding cards to said rolls to be bent, said rolls being arranged in pairs, one pair for bending the ends of the card, the other pair for bending the sides of the card, said plunger having an intermittent step-by-step movement for transferring a card successively to said pairs of bending rolls, and then to said box-carrier, and means for guiding the cards to said plunger in position to be moved to said bending rolls.
50. In a card-bending machine, a frame, a card-conveying plunger, bending rolls comprising substantially vertical angularly movable shafts provided with card-bending surfaces and adjustably mounted in said frame, and means for oscillating said rolls.
55. A card-bending machine, comprising a reciprocating card-feeding plunger having an intermittent step-by-step movement, end-bending rolls, side-bending rolls disposed in a direction at right angles to said end-bending rolls, each of said rolls having an air chamber, means for oscillating said rolls and means for creating an alternate suction and pressure in the chambers of said rolls.
60. In a card-bending device, a frame, a plunger, bending rolls symmetrically arranged in parallel pairs around the path of movement of said plunger, each of said rolls comprising a body portion of triangular cross section having an interior longitudinal chamber, one of the faces of said body portion having a series of perforations extending to said chamber, and means for alternately creating suction and pressure in said chamber.
65. In a card-bending device, a frame, a plunger, card supports in front of said plunger, bending rolls symmetrically arranged in parallel pairs around the path of movement of said plunger, each of said rolls comprising a body portion of triangular cross section having an interior longitudinal chamber, one of the faces of said body portion having a series of perforations extending to said chamber, means for alternately creating suction and pressure in said chamber, means for simultaneously adjusting the rolls of each pair toward or away from each

other, means for oscillating said rolls, and means for operating said plunger.

22. In a card-bending machine, a card-feeding plunger, a pair of substantially vertical, adjustable, and angularly movable bending rolls provided with flat card-edge engaging surfaces extending radially from their axes, and provided with a hollow chamber extending throughout the length of the 10 card-engaging surface, said surfaces being provided with apertures extending into the chamber, and means for creating suction in the chamber.

23. In a card-bending device, the combination of a card-feeding plunger, end-bending rolls and side-bending rolls comprising shafts provided with card-edge engaging surfaces extending radially from the axes of the rolls for engaging the edges of a card, 20 each of said rolls being provided with a hollow chamber extending throughout the length of the card-engaging surface, said card-engaging surfaces having apertures extending into the chamber, and means for creating suction in the chamber.

24. In a card-bending machine, a frame, a plunger, end-bending rolls, side-bending rolls, means for oscillating said side-bending rolls comprising a pinion on one end of each 30 roll, supports for said side-bending rolls, a spindle mounted in said supports, a bevel gear loosely mounted on said spindle, and having a hub portion, a spur gear secured to the hub portion of said bevel gear in mesh 35 with said pinion, a square shaft rotatably journaled in said frame, bevel gears slidably mounted at the opposite end portions of said square shaft in mesh with said spur gears on the hub portion, a power shaft, and 40 means connecting said power shaft with said squared rod to oscillate said rolls.

25. In a card-bending machine, a frame, a card-feeding plunger, a side rail having a slideway, blocks slidably mounted in said 45 slideway, horizontal brackets secured to said blocks, bending rolls comprising horizontally disposed shafts journaled in said brackets, a shaft extending through said blocks and having its ends oppositely threaded for moving said blocks and rolls toward or away from the center of the card-feeding 50 plunger, said rolls being adapted to receive the cards from said plunger and to bend their side flaps around the edges of said 55 plunger, and means for oscillating said rolls.

26. In a card-bending machine, a frame, a plunger, bending-rolls comprising a pair of substantially vertical shafts provided with card-edge receiving surfaces extending 60 radially from their axes for bending the edges of the card around said plunger, a head rail mounted in said frame, and having a slideway, blocks mounted in the slideway, said rolls being journaled in said blocks, 65 a shaft extending through said blocks and

having its ends oppositely threaded for moving said blocks and rolls toward or away from the center of the card-feeding plunger, a bevel gear secured to one end of each roll, a square shaft rotatably journaled at its 70 ends in said frame, a bevel gear slidably mounted at each of the end portions of said square shaft in mesh with the bevel gear of each roll, means for holding each of the gears on said square shaft in mesh with the 75 gears on said rolls, and means for turning said square shaft to impart an oscillating movement to said rolls.

27. A card-feeding and bending device comprising a card hopper, a pneumatic nozzle for gripping the cards, card-stripers in the path of said nozzle, adjustable stop-strips below said strippers, guide-strips between said strippers and said stop strips, bending rolls adjacent said stop strips, and 80 a plunger for feeding the cards to said rolls, said stop strips being adjustable to stop the card in feeding relation to said plunger as the card falls from said strippers.

28. A card-bending device comprising a card-support, two sets of oscillatory rolls for bending the edges of the cards, an intermittently operated plunger for moving the card from said support to one set of said 90 rolls, and then to the other set of rolls, and means for operating said plunger.

29. In a box and label feeding machine, the combination with a box covering machine of suitable supporting frame, of combined card feeding and bending instrumentalities, a box carrier arranged to receive boxes from said instrumentalities, comprising a pivotal swinging frame, and means including a carriage for reciprocally moving said boxes to the platen of a box covering machine, and a label feeding mechanism comprising means including an air suction operating nozzle, an air pump and reciprocating mechanism for gripping and feeding labels from a source of supply to the platen 100 of a box covering machine prior to or simultaneously with the feeding of said boxes to said platen, said boxes being fed on top of said labels on said platen, and means for driving said box covering machine from 105 said box and label feeding machine, and a plunger on said box covering machine arranged to engage said boxes and labels and move them out of the path of said box and label feeding mechanism, into box covering 110 mechanism.

30. In a box and label feeding machine, the combination of the feed hopper and air suction nozzle and the card bending rolls and the reciprocating plunger for feeding 115 the cards to said bending rolls, with a box carrier arranged to receive said box from said card benders and said plunger, said box carrier being provided with a box conveying movement comprising a slideway in 120

which said carrier is reciprocally mounted, and means including a cam and connecting elements for causing said carrier to receive and retain and convey the box from the bending rolls to the platen of a box covering machine.

31. In a card bending machine, the combination with the card feeding plunger, of the end flap, vertically disposed adjustable rolls, and means including gearing, a power driven cam mounted on said machine, and a combination of levers connecting said cam with said gearing arranged and adapted to impart an oscillating movement to said flap bending rolls.

32. In a card bending machine, the combination of the card feeding plunger and the end flap bending rolls, slidably and adjustably mounted in said machine, and provided with gearing arranged to oscillate said rolls, and means for imparting an oscillating movement to said gears and rolls, said means comprising a lever arranged at one end to turn said gears, a lever pivotally connected at one end to said gear turning lever, a spindle rotatively supported in said frame, a lever secured at one end to said spindle and at its opposite end to the opposite end of said lever, a lever secured to the opposite end of said spindle at one end, a power driven cam disk mounted on said machine and provided with a cam groove, and a roller mounted on the opposite end of said spindle-mounted lever, and arranged to project into said groove.

33. In a box and label feeding machine, the combination with the card feeding plunger and the end flap bending rolls, of the side flap bending rolls, said rolls comprising two horizontally positioned shafts, each of which is rotatably supported in an independent bracket, bracket arms being slidably mounted in a vertically disposed slide-way formed in one side of the machine, a threaded rod threaded to said bracket arms and arranged to adjustably move them together in unison toward or away from the center of said plunger, said rolls being adapted to receive the cards from said plunger and to bend their side flaps around the side edges of said plunger, and means including gearing, a power driven cam and suitable connecting members between said cam and said gears, for operatively moving said rolls to operate said rolls.

34. In a box and label feeding machine, the combination with the card feeding plunger, and the end bending rolls, of the side bending rolls comprising horizontally arranged roller shaft-like members, each of which is provided with a flattened portion arranged eccentric to its center, said flattened surface being arranged to receive a card from said plunger, each of said flattened eccentric portions extending through-

out the card engaging surfaces of said rollers and being provided with an air chamber throughout its length and with a plurality of air inlet apertures extending from its card engaging surface into its air chamber, means including piping and an air suction creating mechanism mounted on said machine for creating an air suction force in the air inlet apertures of each of said rolls, and means including gearing, a power driven cam and connecting members for imparting a partial reciprocative or oscillating movement to each of said rolls of sufficient stroke to bend a card around said plunger.

35. In a card bending machine, the combination with the plunger and the end bending rolls, of the side bending rolls, the adjustable vertically disposed slideable supports for said side bending rolls, each of said bending rolls being provided with an air suction chamber having inlet apertures and with an operative air pump cylinder and a power driven shaft mounted on said machine, a cam mounted on said shaft, and means connecting said cam and air pump cylinder and the piping connecting said cylinder with the air chambers of said rolls for creating an air suction force in the air inlet apertures of said side bending rolls.

36. In a card bending machine, the combination with the plunger, of the side bending rolls oscillatively, slidably and adjustably mounted in said machine, means for oscillating said rolls comprising spur gears attached to said rolls, bevel gears meshed with said spur gears, a lever connected to said bevel gears, a connecting rod secured at one end to said lever, a rock arm pivotally connected intermediate of its ends to said machine and pivotally connected at one end to the opposite end of said connecting rod, a forked lever pivotally connected at one of its ends to the opposite end of said crank arm, said forked lever and power driven shaft being journaled on said machine, a cam disk mounted on said shaft and provided with a cam groove, said forked lever being provided with a forked end arranged to straddle said shaft, and a roller pivotally mounted on said forked lever and projecting into the cam groove of said cam, said cam and forked lever and rock arm and connecting rod and the gear supported lever being arranged and adapted to impart an intermittent partial turning reciprocal movement to said gears and rolls, whereby said rolls are caused to turn and bend the side flaps of cards fed to them by said plunger, around the side edges of said plunger.

37. In a card bending machine, the combination with the card feeding intermittent and multiple step movement plunger, of the end and side card bending rolls, of the box carrier, said box carrier comprising a pivot-

- ally swinging and reciprocal movement bar supporting frame consisting of a pair of bars adjustably mounted on a supporting frame to be adjustably moved toward or 5 away from the center of said plunger, to fit boxes of different sizes, each of said bars being provided with slots, box receiving and supporting clips adjustably and slidably mounted in said slots to slide on said bars, 10 said clips comprising angular shaped members having intersecting beveled or inclined sides arranged and adapted to receive the inclined ends and sides of the loose end boxes fed to them by said plunger from said 15 bending rolls, and means for imparting a pivotal, swinging and a reciprocal movement to said box carrier from said bending rolls to a predetermined box delivering point. 20
38. In a box feeding machine, box carrier bars, each of which is provided with a slide-way slot, a pair of right angular shaped clips slidably mounted in the slot of each bar, each being arranged to fit around the 25 corners of a box, means including a clamping nut for adjustably securing said clips to the slots of said bars to receive between them boxes of different sizes. 30
39. In a box feeding machine, a platen, a box carrying and delivering mechanism adapted to deliver boxes made by said machine to said platen of a box covering machine, said mechanism comprising a pair of brackets secured to the opposite side plates 35 of the machine adjacent to said box covering machine, a track member secured to each bracket extending parallel to each other into the machine, a carriage member slidably and reciprocally mounted thereon, said carriage being provided with journal bearings, and a shaft rotatably journaled in said bearings. 40
40. In a box feeding machine, a box carrier and its supporting carriage reciprocally mounted on said machine, cam brackets secured to said machine and provided with a cam rim portion, and roller levers connecting said box carrier to said cam rim whereby said box carrier is caused to swing from 45 a vertically disposed position into a horizontal position during the operative movements of said carriage and box carrier. 50
41. In a box feeding machine, the combination with the box carrier, its supporting carriage and the cam brackets and roller lever running in said cam brackets, of means connected with said carriage for reciprocating the same, said means comprising a link pivotally connected at one end to 55 said carriage, a rock arm pivotally connected intermediate of its ends to said machine, one end of which is pivotally connected to said link and the opposite end of which is 60 pivotally connected to one end of a forked lever, a power driven shaft mounted in said 65 machine, a cam disk provided with a cam groove mounted on said shaft, the forked end of said forked lever being arranged to straddle said shaft, and a roller on said forked lever fitting into said cam groove. 70
42. In combination with the card holding and hopper feeding, the card bending and the box delivering mechanism, of a pneumatically operating apparatus for feeding covering blanks to box covering machines, 75 comprising a co-operating blank receiving and registering station, and the registering station of a box covering machine, and means, including an air impulse nozzle provided with a supply of air under suction 80 and a reciprocal stroke movement operatively arranged and adapted to grip a blank at its registering station and move it to and release and deposit it at the registering station of said box covering machine. 85
43. In combination with the card holding and hopper feeding, the card bending and the box delivering mechanism, of a pneumatically operating apparatus for feeding covering blanks to box covering machines, 90 comprising a blank receiving and registering table and the blank receiving platen of a box covering machine, an air impulse suction and pressure producing mechanism provided with mechanism arranged to grip 95 a blank at said table and to move, release and deposit it on the blank receiving platen of a box covering machine, and means including a reciprocating rod, a cam and co-operating mechanism to which said air impulse blank gripping, moving and releasing mechanism is adjustably secured, for reciprocally moving said air impulse mechanism in operative order to feed blanks from said 100 table to said platen. 105
44. In combination with the card holding and hopper feeding, the card bending and the box delivering mechanism, of a pneumatically operating apparatus for feeding box covering blanks to the platen of a box 110 covering machine, which consists of a supply station, a perforated chambered member arranged to move under and to grip a blank, means for reciprocating said perforated chambered member from said station over to and deposit it on said platen, and means for creating an air suction force in said chambered member at the station table, of sufficient strength to cause said member to grip said blank to it and retain 115 it until it is fed to said platen, and for creating an air discharging pressure of sufficient force to release said blank when on said platen, and co-operating means arranged to so relatively time the reciprocal movements of said perforated chambered member and the air suction and air discharging forces, that said perforated chambered member grips by said suction force 120 said blank and holds it until it is feedingly 125 said blank and holds it until it is feedingly 130

moved on one stroke of its reciprocal movement onto said platen, and that then said air pressure force releases said blank and said perforated chambered member deposits 5 it on said platen.

45. In a box making and box feeding machine, the combination with the automatically feeding hopper, the air suction operating nozzle, the intermittent step 10 movement plunger, the card bending rolls, and the box carrier, with means for operating these various features, of a pneumatic blank feeding apparatus for feeding label blanks to box covering machines, the blank 15 receiving and registering table and the platen of a box covering machine with a plunger bar reciprocally mounted on the frame of said box covering machine, mechanism including cams mounted on the frame 20 of said box covering machine, for operatively reciprocating said bar, an air impulse box adjustably mounted on said bar and arranged to be moved over said platen by said rod, and arranged to grip by air suction 25 force a blank placed on said table in registering relation to said air impulse box, and arranged to release said blank by air pressure force when said blank has been moved from said table to said platen, and means 30 for connecting said air impulse box to an alternatingly operating air suction and air pressure creating mechanism.

46. In a box making and box feeding machine, the combination with the automatically 35 feeding hopper, the air suction operating nozzle, the intermittent step movement plunger, the card bending rolls and the box carrier, with means for operating these various features, of a pneumatically 40 operating apparatus for feeding blank labels to box covering machines, the adjustable blank receiving table or station arranged in operative relation to a box covering machine, adjustable guides on said table 45 arranged to register blanks of various sizes on said table in a position to allow one of their sides to project beyond said table a predetermined distance, an air impulse member arranged to reciprocate to and from 50 said table and the blank receiving platen of said box covering machine, and to move under the side portion of said blank that projects over the edge of said table, a plurality of air inlet and outlet apertures in 55 said impulse member, positioned in said member to be under the projecting side of said blank when said member is close to said table, and under the projecting side of said blank, means for reciprocating said air 60 impulse member to and from said table and the platen of said box covering machine,

and means for providing an alternating supply of air suction and air pressure impulses to said air impulse member, whereby said blank is gripped to said air impulse 65 member by an air suction impulse, and is then conveyed to the platen of said box covering machine, and is deposited thereon by an air pressure impulse, and means including a cam and power conveying elements connecting said cam to said air impulse member for reciprocating the same. 70

47. In a box blank and label feeding machine, in combination, means for feeding a box blank to a bending plunger; means for 75 bending the end flaps; means for bending the side flaps; means for delivering box blanks into a reciprocating box carriage; means for delivering said box over the platen of a box-covering machine and under 80 the box-making form of said machine; and means for delivering a box label over the platen of the box-making machine and under the box blank; all movements being in proper sequence to deliver box blanks 85 and box labels into such position that the box-making form of the box-making machine will coöperate with the box blank and label-feeding machine to unite the box blank and label, and move it away from the 90 box blank and label-feeding machine.

48. In a box-blank and label feeding machine in combination, a box blank hopper, a platen, side and end flap bending means, a box carrier adapted to receive the box 95 blank after the sides and end flaps have been bent up and to convey the same to said platen, and means for reciprocating said box carrier between said platen and the box-making machine, and means for tilting 100 said box carrier from a horizontal position to a nearly vertical position, to receive the box blank.

49. In a box and label feeding machine, in combination with any box-covering machine, means for feeding a box blank into one side of the box-covering machine; means for feeding a gummed label into a box-covering machine from the opposite side of said machine, the said box blank and 110 said gummed label to be positioned one over the other in the box-covering machine in proper relation one to the other to be united and formed into a completed box by the mechanism of the box-covering machine. 115

In testimony whereof I affix my signature in presence of two witnesses.
